Walker Wilson INVENTOR.

H. D. Smith, Attorney.

UNITED STATES PATENT OFFICE.

WALTER WILSON, OF DUNFERMLINE, SCOTLAND.

APPARATUS FOR USE IN MAKING FACED CONCRETE BUILDING-BLOCKS.

1,401,384.

Specification of Letters Patent. Patented Dec. 27, 1921.

Application filed July 17, 1920. Serial No. 397,086.

To all whom it may concern:

Be it known that I, WALTER WILSON, of South Dewar street, Dunfermline, Scotland, a subject of the King of Great Britain, have 5 invented certain new and useful Apparatus for Use in Making Faced Concrete Building-Blocks, (for which I have filed application for patent in Great Britain under date of April 22, 1919,) of which the following is a 10 specification.

This invention relates to the manufacture of faced concrete building blocks or slabs and the like for dwelling houses, factories, and for other structural work.

15 For the purpose of removing the monotonous appearance of concrete walls it is common practice to cover the surface with stone chips or pebbles. The operation, which is known as "pebble dashing," consists in dashing a mixture of chips or pebbles and cement against the surface of the structure to which the mixture adheres. The pebbles or chips adhering to the structure have their outer 20 surfaces covered by a film of cement and, 25 when a high degree of finish is required, this film is cleaned away and the pebbles or chips polished by sand blasting, thereby adding materially to the cost of the operation.

According to this invention concrete blocks, 30 slabs and the like, for use in structural work, are faced in a special manner during the course of manufacture and while in the mold.

The block or slab or the like is first molded face up in a suitable mold, then, while the 35 face of the block or slab is still moist, a coating or surface of cement is laid on the face, then pea-pebbles or stone chips are deposited automatically onto the wet cement and while it is still wet, the surface is washed or 40 sprayed with water, and finally the whole mass is allowed to set in the mold.

After being washed or sprayed with water in the manner described, the block or slab is allowed to set in the mold and when set the 45 pea-pebbles or stone chips will be found to be quite clean so that no subsequent sand blasting or polishing or further treatment is necessary. The pea-pebbles give a clean polished surface while, when stone chips are 50 used, a clean rough cast surface is obtained.

The deposition of the chips or pebbles automatically and evenly on the block or slab or the like in the mold is performed by a 55 novel machine comprising a framework hav-

over the block or slab or the like in the mold. On the frame is a bridge piece to which one end of a sheet of cloth or other suitable flexible material is secured the other end being attached to a roller or equivalent. The arrangement is such that as the cloth is wound off the roller the slide is traversed over the mold above the face of the block or slab or the like therein and stretches the cloth tightly. The chips or pebbles are then 60 sprinkled or laid on the cloth and evenly spread and, thereafter, the cloth is wound onto the roller while being held stretched by the slide which, at the same time, is caused to recede against the action of a weight or 65 equivalent means. As the cloth rolls up, the pebbles or chips are easily and quickly deposited automatically and quite evenly onto the face of the block or slab or the like.

70 A form of the machine for use in carrying out the invention is shown, simply by way of illustration or example, on the accompanying drawings, whereon:

Figure 1 is a longitudinal section through the machine shown in position over a mold 80 for forming concrete blocks or slabs.

Fig. 2 is a cross section on the line X—X

Fig. 1, looking in the direction of the arrow.

Fig. 3 is a plan view of the machine.

Fig. 4 is a view illustrative of the manner 85 in which the chips or pebbles are deposited onto the face of a block or slab.

Referring to the drawings:

A represents the mold with a concrete 90 block or slab formed therein and with the surface B, which is to be faced in accordance with my present invention, uppermost.

The framework of the machine comprises longitudinal members 1 spaced apart to suit the width of the mold and held in place by 95 suitable cross ties 2 at each end. The members 1 are further braced intermediate the ends by bridge pieces 3, 4, and are grooved or recessed, as at 5 to provide guides for a slide 6.

A roller 7 with cloth or other suitable flexible material 8 thereon has its axle 7^a journaled in brackets 9 secured to the lower bridge piece 3. The free end of the cloth or other flexible material is passed along under 105 the slide 6, then up at the front end thereof and then back over the slide and finally it is secured to the upper bridge piece 4, as shown.

Fixed on the roller shaft or axle 7^a is a drum 10 or pulley on which is wound a wire 110

11 whose free end is first passed over a guide pulley 12 attached to the rear end of the slide 6, then over a second guide pulley 13 attached to the front tie 2, after which it is connected to a weight 14.

The roller 7 is conveniently operated by a handle 15 on a chain wheel 16 which is rotatably carried by an upright or bracket 17 on the upper bridge piece 4 and is operably connected with a similar wheel 18, fixed on the roller shaft or axle 7^a, by means of a chain 19.

The operation of facing the block or slab with the machine is as follows:—

After the block or slab has been formed 15 face up in the mold A the face is coated with a layer of cement. The machine is moved over the mold or contrariwise the mold is brought under the machine (Fig. 1) and the slide 6, if not already in the right 20 hand position shown, is moved to this position by operating the handle 15 so as to pay out or unwind the cloth from the roller 7, thereby simultaneously unwinding the wire 11 from the drum 10 and allowing the slide 25 6, under the action of the weight 14 to move forward to the right while acting to maintain the cloth tightly stretched as it is wound off the drum. When the slide with the cloth stretched over the same is in the position 30 shown, marble, granite, whin or other stone chips, or pea-pebbles, as indicated at 20, are sprinkled or laid on the upper surface of the stretched cloth and evenly spread, the spreading being easily done by simply tapping or 35 jarring the framework, or in other manner. Thereafter the cloth 8 is re-wound on to the roller 7 while being held stretched by the slide 6 which, at the same time, is caused to move toward the left hand of the frame 40 against the action of the weight 14. As the cloth rolls up, the chips or pebbles drop automatically, as illustrated at Fig. 4, over the forward edge of the cloth where it passes around the end of the slide and are deposited 45 gradually and quite evenly on to the face B of the concrete block or slab in the mold.

After the pebbles or stone chips have been deposited they are embedded in the wet cement layer and the surface is then washed or 50 sprayed with water in the manner already described, the whole mass being finally left to set in the mold and to form one solid block or slab.

While I have described one preferred form 55 of machine for carrying my invention into effect or practice it is to be understood that various modifications may be made without

departing from the spirit or scope of the invention. For example, the roller 7 may be operated directly, if desired, instead of 60 through the medium of gearing, and spring or other means may be used in lieu of the weight for the proper actuation of the slide 6 relatively to the cloth 8.

There may be a battery of machines fixed 65 in position and the blocks or slabs in their molds be moved thereunder for facing and thereafter be withdrawn mechanically or otherwise.

Having now fully described my invention 70 what I claim and desire to secure by Letters Patent is:—

1. A machine for use in depositing stone chips or pebbles on to molded concrete blocks and the like, comprising a framework, a slide 75 within the framework, a roller carried by the framework, flexible material secured at its one end and passed around the slide on to the roller, and means whereby as the flexible material is wound on and off the roller the 80 slide is simultaneously traversed within the framework while acting to maintain the flexible material tightly stretched.

2. A machine for use in depositing stone chips or pebbles on to concrete blocks and 85 the like, comprising a framework, a slide within the framework, a roller carried by the framework, flexible material secured at its one end and passed around the slide on to the roller, means for rotating the roller, and 90 means acting in conjunction with the slide and roller whereby as the flexible material is wound on and off the roller the slide is simultaneously traversed within the framework while acting to maintain the flexible 95 material tightly stretched.

3. A machine for use in depositing stone chips or pebbles on to concrete blocks and the like, comprising a framework, a slide within 100 the framework, flexible material secured at its one end to the framework and passed around the slide on to the roller, chain gear for rotating the roller, and gravity means acting in conjunction with the slide whereby as the flexible material is wound on and off 105 the roller the slide is simultaneously moved within the frame while acting to maintain the cloth tightly stretched.

In testimony whereof I affix my signature in presence of two witnesses.

WALTER WILSON.
